Primary Examiner — John Windmuller*Assistant Examiner* — John R Yeh(74) *Attorney, Agent, or Firm* — Carol N. Green Kaul, Esq.(57) **CLAIM**

The ornamental design for an electronic communication device with a touchscreen display for reviewing advertisements, as shown and described.

DESCRIPTION

FIG. 1 is a front perspective view of the electronic communication device with a touchscreen display for reviewing advertisements.

FIG. 2 is a rear perspective view of the electronic communication device with a touchscreen display for reviewing advertisements.

FIG. 3 is a front view of the electronic communication device with a touchscreen display for reviewing advertisements.

FIG. 4 is a rear view of the electronic communication device with a touchscreen display for reviewing advertisements.

FIG. 5 is a right side view of the electronic communication device with a touchscreen display for reviewing advertisements.

FIG. 6 is a left side view of the electronic communication device with a touchscreen display for reviewing advertisements.

FIG. 7 is a top view of the electronic communication device with a touchscreen display for reviewing advertisements; and,

FIG. 8 is a bottom view of the electronic communication device with a touchscreen display for reviewing advertisements.

The broken lines in the figures represent features of the device which form no part of the claimed design.
